UNITED STATES PATENT OFFICE.

ROBERT W. SCOTT, OF BOSTON, MASSACHUSETTS, ASSIGNOR, BY MESNE ASSIGNMENTS,
TO SCOTT & WILLIAMS, INCORPORATED, A CORPORATION OF MASSACHUSETTS.

CIRCULAR-KNITTING MACHINE.

1,324,628.

Specification of Letters Patent.

Patented Dec. 9, 1919.

Application filed July 14, 1915. Serial No. 39,887.

To all whom it may concern:

Be it known that I, ROBERT W. SCOTT, a citizen of the United States, and resident of Boston, in the county of Suffolk and State of Massachusetts, have invented certain new and useful Improvements in Circular-Knitting Machines, of which the following is a specification.

My invention relates to knitting machines, one object being to provide improved and simplified devices for knitting fine gage fabrics, and stockings having reciprocally to knit heels and toes. Other objects are to provide for making such fabrics by the operation of needles having relatively long hooks in existing hosiery knitting machines, by enabling them to employ for rotary and reciprocatory knitting such needles, of which one species having spring hooks and latches is disclosed in my Letters Patent No. 1,097,732, dated May 26, 1914. I have herein illustrated my invention as comprising changes in a latch-needle knitting machine of the type described and claimed in my application Serial No. 746,070 filed February 3, 1913, (Letters Patent No. 1,152,850, September 7, 1915) but my invention is independent of the particular machine in which it may be utilized, one feature thereof being provision of means for adapting existing latch-needle machines of various types to make fabrics of a superior character and finer gage. In the accompanying drawings, Figure 1 is a diagram development of the cam ring and yarn guides showing a needle and paths taken by the needles during rotary and reciprocatory knitting;

Fig. 2 is a diagram plan illustrating the relation of the yarn feed devices to the knitting cams.

When attempting to knit fabrics of fine gage on ordinary latch needles of the prior art spaced closely, the needles produce fabric permanently of too great a width, which can not be altered by finishing operations.

The fabric of reciprocally knit heels and toes, as one instance, lies permanently too wide relatively to the size of the series of needles upon which it is knit, remaining too large after finishing even when the ankle and foot can be stretched in length and shrunk in width to the desired extent. By use of needles of the sort indicated with

means for operating them and means for feeding yarn now to be described, I have successfully reduced the width of the fabric, including the heels and toes, relatively to the size of the series of needles. The drawing shows, for purposes of illustration only, a machine equipped with the needles 1 of my said patent, having the usual operating butts, comparatively long spring hooks 3, and short latches 5, situated at a relatively large distance from the tip of the needle. But any needle having a comparatively long hook, whether rigid or of spring metal, is within the scope of my invention.

Yarn changing yarn-guides F¹, F², F³, F⁴, F⁵, preferably similar to those of my said application are, in any desired number, movable in a slot in a latch-guard 550 closed at the bottom, as by a throat-plate 559. Said yarn-guides may be of any construction permitting one at a time to be removed into an operative position such as shown for guide F¹.

The needle cams, see Fig. 1, may comprise a leading stitch cam 7 and a following stitch cam 6, a top center cam 8 and a bottom center cam 9 defining between them a flat or level path for needles about to receive yarn, each cam when leading advancing the needles at its top or back to clear their latches, and when following retracting the needles at surface a or b constituting the active stitch-drawing slope of the stitch cam. The machine is provided with usual devices for causing relative rotation between the series of needles and the needle cams and yarn guides, and at times relative reciprocation between said parts, and with narrowing and widening devices to make heel and toe pockets. Preferred devices for these purposes are disclosed in my said application.

For a given length of stitch drawn by such needles receding through an old loop detained against movement with the needle in any manner, as at the plane P usually defined by movable web-holders (not shown), the place for feeding yarn under the hooks of the needles is carried farther beneath said plane P than in the case of ordinary latch-needles, and the tip of the hook is elevated farther above loops detained at the web-holders to clear the old loops beneath the hook or latch. The distance from the tips of the needles to the points of the open latches 5, when the

needles of my said patent are in use, may be nearly the same as that between tip and point of open latch of ordinary latch needles, the necessary movement of the 5 needles to knit in this case being of the same extent and kind as in the case of ordinary needles. Knitting cams of prior machines, such as those illustrated may thus be employed without change, but the place 10 at which yarn can be supplied operatively to the needles is, as a consequence of the length between latch and tip, much nearer the knocking-over plane P, and is narrower, the form of the wave of movement being the 15 same, than is the case when ordinary latch-needles are employed.

Needles 1 traveling between cams 8 and 9 present their place for feeding yarn beneath open hook 3, as indicated between 20 lines p, p' Fig. 1, on a level above plane P at and following the position of the first needle to move down the stitch cam. I provide for feeding the yarn with enough lead to lie against a considerable number of said 25 needles at said level and between the lines p, p' a wrapping of yarn lying upon the needles between a needle completely beneath plane P and the yarn guide at a relatively flat angle to the horizontal. The 30 point of hook 3 of said first needle to move downward will then be landed over said yarn by its movement while in the middle of a series of needles against the faces of each of which the yarn lies, and by which the 35 yarn is frictionally supported. The number of needles to receive the yarn in advance of the first needle to move to land its hook over the yarn may be increased beyond the number necessary to insure operation with 40 out detriment to the operation, so long as a separation or lead of the yarn-feeding point from the first needle moving down a stitch cam is sufficient to insure accurate landing under the hooks. It will be understood 45 that the minimum degree of lead for the yarn may vary with the spacing and gage of the needles, with the dimensions of their hooks, with the kind or tension of the yarn, the number of separate yarns fed together, the distance from the face of the 50 needles of the yarn delivery opening, and other variable conditions apparent to those skilled in the art, but in all cases the minimum lead will be such as to lay the yarn upon the needles as described and will exceed that usual for short-hook needles working under similar conditions.

In prior machines needles moving in either direction operatively take yarn from 60 the guide last passed by the needles, but by reason of the increased lead to be provided to secure feeding the long-hooked needles, a yarn fed from a position much nearer the following stitch cam than the 65 plane A—A central between the stitch cams

will not be taken. I have therefore arranged the yarn guide F¹ for the heel and toe yarn or yarns fed during reciprocation in said plane, to deliver its yarn directly from a yarn bore f therein, whereby during 70 reciprocation the yarn from said guide enters the needles at sufficient lead with respect to knitting waves both at cam 6 and cam 7. I prefer to bring about this relative position of the yarn guide F¹ by shifting 75 the cam-carrier about the center of the machine, as shown, so that radial plane A—A at the cams is thrown out of parallel with the yarn-guides, and to coincide with the active end of the last-passed guide F in the 80 direction for rotary knitting. The narrowing pickers 650 are moved with the cams, but the latch-ring 550, guides F¹, F⁵ operating devices therefore, and other parts may remain as in the prior machines. 85

The relation of the knitting waves to the yarn guides is shown in Fig. 1 by solid and broken lines and corresponding arrows.

The yarns from yarn guides F², F³, F⁴, and F⁵, are in use during rotation only, the 90 cam 6 then being the retracting cam. Yarns from any one of said guides reeveing either from their yarn bores or from an edge of plate 559 are at a lead greater than yarn from guide F¹, and are operatively positioned. 95

One consequence of shifting the knitting cams with respect to their series of yarn-guides is to bring the gap or throat in the latch-ring for said guides opposite a part 100 of the advancing wave caused by cam 7 in the direction for rotation. The latches 5 are prevented from opening in the open throat by a thin extension 558 of the latch-guard surface, which extension 105 may be a part of plate 559. Such of the yarn-guides as stand behind said extension when down and in operation enter their yarns between the rapidly moving needles at their tips, here extending well above plate 110 558, and by the movement of the needles said yarns are swept to the level for proper feeding at plate 559. 115

What I claim is:

1. A knitting machine having in combination latch needles with long hooks, stitch cams adapted for rotary and reciprocatory knitting, and means for feeding yarn from a point in advance of the active stitch cam during rotary knitting at a relatively flat 120 angle, to lie under the points of the hooks of a plurality of needles about to be but not yet retracted to the stitching point by said active cam, and against the faces of a plurality of needles between said stitch cam and said yarn feeding means, whereby a needle actuated to land its hook over the yarn is in the middle of a series of needles against which the yarn lies. 125

2. A knitting machine adapted for rotary 130

- and reciprocatory knitting and having in combination needles having relatively long hooks, leading and following reciprocal stitch cams, and means for guiding yarn to 5 said needles from a point near the needles near the plane of maximum retraction in the needles caused by said stitch cams and a substantial distance in advance of any of the needles being actuated by the following 10 stitch cam when knitting in either direction, whereby the yarn lies relatively near to said plane and under the hooks of a number of needles in advance of those being actuated by said stitch cam.
- 15 3. A knitting machine adapted for knitting upon a series of needles having long hooks and latches defining a place for feeding said needles removed from their tips and narrow in extent, comprising in combination 20 an advancing or clearing cam and a following stitch cam, cams for maintaining said needles at a level between said advancing and stitch cams, and means for guiding yarn in a plane intercepting said place 25 for feeding and nearly parallel to the position of the places for feeding of a series of needles at said level, whereby the yarn contacts with said places for feeding of a plurality of said needles during their maintenance at said level.
- 30 4. A knitting machine adapted for rotary and reciprocatory knitting and provided with needles having long thin hooks and relatively short latches, and leading and 35 following stitch-cams, in combination with means for feeding a yarn for reciprocatory knitting from a guide substantially midway between said stitch cams and from a point in or near the level defined by the open 40 latches to lie against needles prior to their actuation by said cams, and means for feeding other yarns for rotary knitting from points in said level in advance of said guide and at different distances from said following stitch cam.
- 45 5. A circular knitting machine having in combination a latch guard member having a surface concentric with the rotary element, a slot in said member central upon a 50 radial plane, parallel yarn-changing yarn guides working in said slot, needles having long hooks and latches and reciprocal stitch-

cams symmetrically placed with respect to a radial plane intersecting a yarn guide at one side of said slot.

55

6. The combination in a knitting machine of needles, a stitch cam and an advancing cam, a yarn-guide movable into and out of position to enter its yarn between needles while they are in the position to which they 60 are advanced by said advancing cam and a latch-guard for said advanced needles exposing their tips to receive said yarn.

7. A circular knitting machine having in combination latch needles having long hooks 65 and cams therefor having an advancing surface for clearing the needle latches operative ahead of a retracting or stitch cam, a latch guard member having a slot therein, a series of yarn-changing yarn guides in said 70 slot some of which when operatively positioned are opposite needles while they are in the position to which they are advanced by said advancing surface, and an extension of said latch-guard member at said slot 75 covering the latches and exposing the tips of said advanced needles, to receive yarn between adjacent advanced needles from an operatively positioned yarn-guide.

8. A knitting machine adapted for reciprocatory knitting and for rotary knitting in one direction, and having needles having spring beards and latches, leading and following reciprocal stitch cams, the leading cam being adapted to advance the needles 80 from their normal position, and means for feeding a yarn for reciprocal knitting to said needles from a point near the needles and substantially in advance of the following stitch cam, in each reciprocal direction, 85 in combination with a series of yarn guides adapted for yarn-changing having yarn delivery openings situated when active in advance, in the direction for rotary knitting, of said yarn feeding means, and at a part of 90 the wave in the needles caused by said leading stitch cam, said yarn-guides being adapted to enter their yarns between adjacent needles while said needles are in said wave.

In testimony whereof, I have signed my 100 name to this specification.

ROBERT W. SCOTT.
